UNITED STATES PATENT OFFICE.

MYER CHAREN, OF PHILADELPHIA, PENNSYLVANIA.

TOOTH SHADE GUIDE.

Application filed March 12, 1926. Serial No. 94,180.

My invention relates particularly to that class of dental devices commonly known as tooth shade-guides, and employed by dentists in determining by comparison the particular shade of artificial stock teeth that may be substituted for the natural teeth of the patient.

The principal object of my invention is to provide a simplified and inexpensive holder for sample teeth, which may be constructed of two pieces of sheet material, formed to provide means for individually engaging removable tooth mountings by such pressure as to prevent their accidental displacement, but to readily permit their manual removal from said holder.

A further object is to provide a holder stamped from a single piece of sheet metal and bent to the shape of an elongated, tubular holder of rectangular cross-section within which is located a one piece member of spring metal having stamped out therefrom resilient tongues each to accommodate a sample tooth holder opposite each tongue of which is arranged a tooth mounting aperture.

A further object resides in the provision of general details of construction and arrangement and combination of parts for attaining the foregoing objects.

The invention consists of the novel construction hereinafter described and finally claimed.

The nature, characteristic features and scope of the invention will be more fully understood from the following description taken in connection with the accompanying drawings forming part hereof, and in which:

Fig. 1, is a view in elevation of a tooth shade holder embodying the invention, parts being broken away for clearer illustration.

Fig. 2, is a fragmentary view in elevation of the spring tongue plate.

Fig. 3, is a view in cross-section taken upon the line 3—3 of Fig. 1.

Fig. 4, is a view in cross-section taken upon the line 4—4 of Fig. 2.

Fig. 5, is a view of a sample tooth and its mounting detached; and

Fig. 6, is an edge view of the holder illustrating the apertures for receiving the tooth mountings.

For the purpose of illustrating my invention I have shown in the accompanying drawings one form thereof which is at present preferred by me, since the same has been found in practice to give satisfactory and reliable results, although it is to be understood that the

various instrumentalities of which my invention consists can be variously arranged and organized and that my invention is not limited to the precise arrangement and organization of the instrumentalities as herein shown and described.

In the drawings the holder proper is formed of one piece of material, in practice sheet metal, and is bent to form an elongated casing of hollow and rectangular cross-section. The holder so formed is designated by reference numeral 1 and the meeting edges of the sheet are designated 2. One of the walls of the holder, that designated 3 in the drawings, is provided with a plurality of rectangular apertures 4, see Fig. 6. This wall 3 in practice comprises the top of the casing. Adapted for detachable insertion in said apertures 4 of wall 3 are the mountings 5 pivotally carrying as at 6 the sample teeth 7. Having a snug fit with the holder proper is a spring metal member formed from a single sheet of material and having stamped therefrom a plurality of resilient tongues 8, one of which is arranged opposite each of the apertures 4. In the drawings the member is designated 8 and in cross-section, as shown in Fig. 4, is convexed and from this convexed portion are stamped the resilient tongues 9. As before stated, a tongue 9 is opposite an aperture 4 so that when a mounting 5 is introduced to an aperture 4 said mounting 5 impinges against a resilient tongue so that a mounting is removably, yet firmly held in place between the inner face of a tongue 9 and the inner surface of the front face 10 of a holder, see Fig. 3.

It will now be apparent that I have devised a novel and useful construction which embodies the features of advantage enumerated as desirable in the statement of the invention and the above description and while I have in the present instance shown and described the preferred embodiment thereof which has been found in practice to give satisfactory and reliable results, it is to be understood that the same is susceptible of modification in various particulars without departing from the spirit or scope of the invention or sacrificing any of its advantages.

What I claim is:

A device of the character stated comprising an elongated, tubular casing of substantially rectangular cross-section, formed of a single, elongated piece of sheet metal, bent longitudinally to form four longitudinal

walls, one wall of said casing being indented throughout the major portion of the casing extent and the opposed wall of said casing being flat, the top wall of said casing being 5 provided with a plurality of shade guide receiving slots of uniform size, and a single, elongated plate of sheet metal fitted within said casing between said indented wall and flat wall, said plate having a transverse curve 10 at the extremities of said plate abutting against said flat wall, said plate having

stamped out therefrom a plurality of resilient tongues of uniform size one tongue being arranged opposite each slot, whereby when a dental mounting is introduced between said indented wall and said plate said plate yields sufficiently to cause clamping of said mounting between said indented wall and plate. 15

In witness whereof, I have hereunto signed my name.

MYER CHAREN.
